US00D764832S

(12) United States Design Patent (10) Patent No.: US D764,832 S
(45) Date of Patent: * Aug. 30, 2016

(54) SOAP DISPENSER

(71) Applicant: CREAVEST, Tiegem (BE)
(72) Inventor: Sophie Douterloigne, Tiegem (BE)
() Term: 15 Years
(21) Appl. No.: 35/500,267
(22) Filed: May 20, 2015

(80) Hague Agreement Data

Int. Filing Date: May 20, 2015
Int. Reg. No.: DM/086897
Int. Reg. Date: May 20, 2015
Int. Reg. Pub. Date: Nov. 20, 2015

(30) Foreign Application Priority Data

Nov. 24, 2014 (EP) 002584029-0001
(51) LOC (10) Cl. 23-02
(52) U.S. Cl.
USPC D6/545

(58) Field of Classification Search

USPC D6/512, 524, 542, 545, 553
CPC G01F 11/00; G01F 11/021; G01F 11/262;
G01F 13/00; G01F 13/001; A47K 5/00;
A47K 5/06; A47K 5/12; A47K 5/1207;
A47K 5/1209
